TRANSPOSITION KEYBOARD FOR PIANOS

Carl Hagstrom, New York, N. Y.

Application March 31, 1939, Serial No. 265,124

4 Claims. (Cl. 84—447)

This invention relates to new and useful improvements in a transposition keyboard for pianos.

The invention has for an object the construction of a piano keyboard which is characterized by a specific arrangement by which the keys may be shifted into various lateral positions and held in these positions to transpose the keyboard.

10 Furthermore, it is proposed that the keys be associated with hammer mechanism which moves relative to the strings of the piano during the transposition mentioned.

15 Still further the invention proposes a novel arrangement for supporting the keys and the hammers and for moving these parts as desired.

Another object of this invention resides in a novel arrangement by which the keys may be shifted forwards or rearwards through predetermined distances to affect the hammer action 20 for modulating the tone of the piano.

25 For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

30 Fig. 1 is a fragmentary perspective view of a keyboard for a piano constructed according to this invention.

Fig. 2 is a fragmentary vertical sectional view 35 taken on the line 2—2 of Fig. 1, this view showing a portion of hammer mechanism and its particular relationship to the keys.

Fig. 3 is a fragmentary vertical sectional view taken on the line 3—3 of Fig. 2.

Fig. 4 is a plan view looking in the direction 40 of the line 4—4 of Fig. 2.

Fig. 5 is a front elevational view of Fig. 2 with certain parts removed to disclose interior parts.

Fig. 6 is a bottom elevational view of a portion 45 of the hammer mechanism and a portion of the strings of the piano.

Fig. 7 is a similar view to Fig. 2, but illustrating the modified form of the invention.

The transposition keyboard for pianos, according to this invention, includes a carrier 10 laterally slidably mounted in said piano and supporting a plurality of keys 11 and 12 which extend forwards and rearwards. The carrier 10 is supported by several rollers 13. These rollers are mounted upon brackets 14 mounted upon 55 the bottom of the carrier. The brackets 14 ex-

tend into grooves 15 formed in a frame portion 16 of the piano body. The rollers 13 engage in narrow grooves 17 formed in the bases of the grooves 15.

Guiding pins 18 are mounted upon the carrier 10 and extend into limiting grooves 19 formed in the frame 16 for limiting motion of the carrier laterally towards the right or the left as desired. The keys 11 and 12 are supported upon the carrier 10 by conventional vertical 10 pintles 20. These pintles have small leaf springs 21 supported upon their upper ends and engaging the top faces of the keys for individually holding the keys in horizontal positions. The arrangement is such that the front ends of the 15 keys may be depressed so that the rear ends move upwards, and when the keys are released they seek normal horizontal positions. Stop pins 22 are mounted upon the carrier 10 and engage into recessed openings 23 formed in the 20 bottom faces of the keys to limit downward depression thereof.

An arrangement is provided for locking the carrier 10 in various lateral positions. This arrangement includes a rod 25 pivotally mounted 25 to move up and down by a pintle 26 upon the carrier 10 and extending forwards. A bracket 27 is also mounted upon the carrier 10 and a tension spring 28 is connected between the bracket and the rod 25 for normally urging the 30 rod upwards. The rod 25 is provided with a head 29 at its outer end by which it may be manually moved. The rod 25 extends through an opening 30 formed in a plate 31 mounted upon the front of the piano. This opening 30 has a plurality of recessed top branches 32 into which the rod 25 is urged by the spring 28. The arrangement is such that the rod 25 may be manually pivoted downwards to remove same from one of the branches 32, and then the rod may be 35 moved laterally in one direction or the other, along the opening 30 to a new position. Then when the rod 25 is released it will move upwards and engage a different one of the branch openings 32.

45 A hammer mechanism is associated with the keys. This hammer mechanism includes a transmission hammer 34 mounted on the inner end of each of the keys and cooperative with an operator hammer 35 pivotally supported by a 50 pintle 36 mounted upon a bracket 37 mounted on a frame 38. This frame 38 has a back plate 39 formed with slots 40 through which supporting elements 41 pass. These supporting elements 41 engage the body portion 42 of the piano body, 55

so that the frame 38, 39 is slidably supported. Rods 43 connect the frame 38, 39 with the carrier 10 (see Fig. 5) so that these parts move in unison with each other. At the sides of the piano, at the keyboard area, there are cover plates 44 beneath which there is a recessed portion 45 into which the end keys of the keyboard may be moved when the keyboard is transposed in one direction or the other.

10 In Fig. 6 the operator hammers 35 are shown in specific relation to the strings 46 of the piano string board. It should be understood that when the keyboard is transposed the keys will move relative to the strings 46 and so there is a transposition of the keys of the piano.

15 In Fig. 7 a modified form of the invention has been disclosed which distinguishes from the prior form in the fact that an arrangement has been provided to modulate the hammer action 20 of the piano. In this form of the invention the carrier 10' consists of an upper layer 10^a and a lower layer 10^b. These layers are adjustably connected to move forwards and rearwards relative to each other by fastening elements 50 25 mounted upon the lower layer and engaging through slots 51 formed in the upper layer. Leaf springs 52 are also mounted upon the fastening elements and have resilient front ends 52^a which are adapted to engage in certain of a plurality 30 of recesses 53 formed in the top layer 10^a. The rod 25 is mounted upon the top layer 10^a. The bottom layer 10^b is provided with the rollers 71 which operate in the grooves as previously mentioned. The support plate 29 is connected with 35 the bottom layer 10^b at the points 39^a (see Fig. 7). In other respects this form of the invention is identical to the prior form and like parts have been designated by the same reference numerals.

40 The operation of the form of the device shown in Fig. 7 is as follows:

The handle 29 may be moved laterally for shifting the carrier 10' laterally to transpose the keyboard thereof. When desired the layer 10^a 45 may be moved forwards or rearwards relative to the layer 10^b by pulling or pushing the handle 29. A change of this type will control the distances 50 through which the transmission hammers 34 move the operator hammers 35. This will modulate the piano. Adjustments may thus be made to strike the string harder or not so hard without varying the touch upon the keys of the piano.

55 While I have illustrated and described the preferred embodiments of my invention, it is to be understood that I do not limit myself to the precise constructions herein disclosed and the right is reserved to all changes and modifications coming within the scope of the invention as defined in the appended claims.

60 Having thus described my invention, what I claim as new, and desire to secure by United States Letters Patent is:

1. In a transposition keyboard for pianos, a carrier consisting of a lower layer and an upper layer resting on said lower layer and having elongated slots extending forwards and rearwards of said piano and a plurality of grooves to the front of said slots, means for supporting said lower layer to be movable laterally of said piano, keys mounted on the upper layer of said carrier, a hammer mechanism for each of said keys to be actuated by said keys to strike strings 65 stationarily mounted in said piano, said hammer mechanism comprising one section pivotally mounted in said piano and a second section 70 mounted in said piano and a second section

mounted on said keys and disposed to the rear of said first section to strike and pivot said first section to engage its respective string when said keys are actuated, and pins extending from said lower layer through elongated 5 slots for slidably supporting said upper layer on said lower layer to move forwards and rearwards of said piano and vary the distance between the sections of said hammer mechanisms.

2. In a transposition keyboard for pianos, a 10 carrier consisting of a lower layer and an upper layer resting on said lower layer and having elongated slots extending forwards and rearwards of said piano and a plurality of grooves to the front of said slots, means for supporting said 15 lower layer to be movable laterally of said piano, keys mounted on the upper layer of said carrier, a hammer mechanism for each of said keys to be actuated by said keys to strike strings stationarily mounted in said piano, said hammer mechanisms comprising one section pivotally mounted in said piano and a second section mounted on 20 said keys and disposed to the rear of said first section to strike and pivot said first section to engage its respective string when said keys are 25 actuated, and pins extending from said lower layer through elongated slots for slidably supporting said upper layer on said lower layer to move forwards and rearwards of said piano and vary the distance between the sections of 30 said hammer mechanisms, and means on said pins engaging said upper layer for releasably holding said upper layer in various shifted positions on said lower layer.

3. In a transposition keyboard for pianos, a 35 carrier consisting of a lower layer and an upper layer resting on said lower layer and having elongated slots extending forwards and rearwards of said piano and a plurality of grooves to the front of said slots, means for supporting said lower layer to be movable laterally of said piano, keys mounted on the upper layer of said carrier, a hammer mechanism for each of said keys to strike strings stationarily mounted in said piano, said 40 hammer mechanisms comprising one section pivotally mounted in said piano and a second section mounted on said keys and disposed to the rear of said first section to strike and pivot said first section to engage its respective string when 45 said keys are actuated, and pins extending from said lower layer through elongated slots for slidably supporting said upper layer on said lower layer to move forwards and rearwards of said piano and vary the distance between the sections of 50 said hammer mechanisms, and means on said pins engaging said upper layer for releasably holding said upper layer in various shifted positions on said lower layer, comprising a leaf 55 spring for each of said slots, each of said springs having one of its ends mounted on the pin of its respective slot and the other of its ends selectively engageable into one of the plurality of grooves formed to the front of its respective slot.

4. In a transposition keyboard for pianos, a 65 carrier consisting of a lower layer and an upper layer resting on said lower layer and having elongated slots extending forwards and rearwards of said piano and a plurality of grooves to the front of said slots, means for supporting said 70 lower layer to be movable laterally of said piano, keys mounted on the upper layer of said carrier, a hammer mechanism for each of said keys to be actuated by said keys to strike strings stationarily mounted in said piano, said hammer mech- 75

anisms comprising one section pivotally mounted in said piano and a second section mounted on said keys and disposed to the rear of said first section to strike and pivot said first section to engage its respective string when said keys are actuated, and pins extending from said lower layer through said elongated slots for slidably supporting said upper layer on said lower layer to move forwards and rearwards of said piano and vary the distance between the sections of said hammer mechanisms, and means on said

pins engaging said upper layer for releasably holding said upper layer in various shifted positions on said lower layer, comprising a leaf spring for each of said slots, each of said springs having one of its ends mounted on the pin of its respective slot and the other of its ends selectively engageable into one of the plurality of grooves formed to the front of its respective slot, each of said grooves being extended laterally of said piano and arranged one in back of the other. 5 10
